GAME APPARATUS

John W. MacClatchie, Los Angeles, and Tilmon C. Alexander, Compton, Calif.; said Alexander assignor to said MacClatchie doing business as MacClatchie Manufacturing Company, Compton, Calif.

Application July 2, 1934, Serial No. 733,432

28 Claims. (Cl. 273—144)

This invention is a game apparatus for playing the game of draw poker; and has for its object to provide an apparatus containing a plurality of independent and separately movable 5 elements representing the respective cards of a usual deck of playing cards, and which may comprise balls or the like having the respective card symbols displayed thereon, and adapted to have a number of said card-elements corresponding 10 to the number of cards in a hand, mechanically supplied or dealt to each of a plurality of stations of the apparatus which are provided for the respective players, with the hand which is dealt to each station visible to the player at said station but concealed from the players at the other stations, and including means whereby such of the card-elements at each station as the player wishes to discard from his hand, may be mechanically removed from the station, and also 15 including means whereby the proper number of card-elements to again fill the respective hands may then be mechanically supplied to the respective stations.

It is a further object of the invention to dump 20 and return all of the card-elements to a common container after the play of each hand, and to thoroughly mix or shuffle the plurality of card-elements so that upon the next deal the hand for each station will be mechanically chance determined from the shuffled plurality of card-elements which correspond to a shuffled deck of 25 cards.

It is a still further object of the invention to selectively remove from each station any desired 30 number of the card-elements dealt thereto which the player wishes to discard, with the discarded card-elements temporarily kept separate from the plurality of card-elements from which the stations are supplied, so that the draw to refill the 35 hands at the respective stations will be chance determined from the remainder of the originally shuffled deck without the discard being included therein.

It is a still further object of the invention to 40 provide means for controlling the number of card-elements supplied to each station, whereby a maximum number of card-elements corresponding to a full hand, e. g. five card-elements, may be supplied to each station upon initial actuation of the control means, and any selected 45 number of card-elements up to and including the maximum and corresponding to each player's announced discard, may be supplied to the respective stations after the discard and upon secondary actuation of the control means. It is a still further object of the invention to lock the apparatus against removal of card-elements from a station during and after the secondary actuation 50 of the control means and to also lock the control means against further actuation after

its secondary actuation, with said locking means remaining operative until the entire mechanism is released at the end of the play for dumping and returning all of the card-elements of the hands to the common container, ready for dealing new hands to the respective stations. 5

It is a still further object of the invention to provide a coin-control for the apparatus, whereby it is locked against initial dealing of hands to the respective stations until a proper coin has 10 been inserted, and whereby dumping and returning the hands to the common container at the end of the play relocks the entire mechanism until a new coin is inserted.

Further objects of the invention will be readily 15 understood from the following description of the accompanying drawings in which:

Fig. 1 is a plan view of the apparatus.

Fig. 2 is a front elevation.

Fig. 3 is a vertical section in the line 3—3 of 20 Fig. 1.

Fig. 4 is a vertical section on the line 4—4 of Fig. 3, showing the parts in their position at the end of play of a hand.

Fig. 5 is a similar view showing the parts ready 25 for play of a new hand.

Figs. 6, 7, and 8 are vertical sections on the line 6—6 of Fig. 1, showing successive stages of operation.

Fig. 9 is a vertical section on the line 9—9 of 30 Fig. 2.

Fig. 10 is a horizontal section on the line 10—10 of Fig. 9.

Fig. 11 is a vertical section on the line 11—11 of Fig. 10. 35

Figs. 12, 13, and 14 are vertical sections on the lines 12—12, 13—13, 14—14 respectively of Fig. 6.

Fig. 15 is a vertical section on the line 15—15 of Fig. 8. 40

The apparatus comprises a main housing 1 which may be mounted upon a pedestal 2 so that the players may stand around the housing; and the main housing has a plurality of stations 3 for the respective players, shown in the present instance as four in number and arranged at the 45 respective vertical walls of a quadrilateral rectangular main housing. Each player standing in front of his station may thus observe his own hand displayed at his station, but the housing 1 shields the hand at each station from observation by the other players standing in front of their own stations. 50

As shown at Figs. 1 and 2 a hopper 4 is mounted at the center of housing 1 adjacent its upper end with a discharge tube 5 extending from the hopper to each of the stations 3; and an elevator 6 is adapted for vertical movement in one corner of the front of casing 1, and when in its elevated position communicates with a chute 7 leading to the hopper 4 and when in its lowered 60

position is received in a well 8 depending from the housing 1, with the base of the housing sloping downwardly toward the well as shown at 9.

A handle 10 for operating the elevator projects 5 through a vertical slot 11 in the front wall of housing 1, at one side of the station 3 for that player who stands at the front wall of the housing 10 and who is designated the "dealer", and a coin control 12 is preferably provided at the front 15 wall of the housing at the opposite side of its station 3. A set of control knobs 13 is provided for each of the discharge tubes 5, with the sets of knobs preferably positioned for convenient actuation by the "dealer"; and in the present 20 instance are shown as projecting from the top of housing 1 above the respective discharge tubes 5, where the "dealer" by reaching over the top of the housing has access to all of the knobs. The "dealer" in addition to playing his own hand at 25 his station 3, inserts a coin at the control 12 and operates the elevator 6 at the start of play of each hand, and also shuffles the card-elements as hereinafter described, and by manipulating the knobs 13 deals a hand to each player, and subsequently deals the number of card-elements requested by each player after his discard.

The card-elements represent the cards of a usual deck of playing cards and are separate from one another and independently movable for 30 chance determined display of any combination of a plurality of said separate elements at each of the stations 3, and for this purpose are shown as balls 15 bearing symbols 16 designating the 35 respective cards of a deck, and adapted to be dumped into hopper 4 so as to gravitate through tubes 5 to the respective stations 3.

As an instance of this arrangement the base of hopper 4 preferably curves downwardly toward its periphery to form an annular trough 40 17, and the tubes 5 communicate with this trough via equidistantly circumferentially spaced discharge posts 18. Each tube 5 is of a diameter to receive and position the balls one behind another, and is of a length to hold a number of 45 balls sufficient to furnish the initial hand for its station 3 and also furnish such number of balls as the player at the station may desire to draw after he has discarded. For this purpose each tube is of a minimum length to hold at least 50 ten balls, so as to initially furnish a hand of five cards and also permit any desired discard up to the full hand with a corresponding number of balls subsequently supplied to refill the hand, and is of a maximum length to insure there 55 being at least ten balls left in the hopper for reception in the last discharge tube which is filled. In practice each tube may hold just ten balls, so that when a full deck of fifty-two cards is used, each tube may be filled to capacity and 60 still leave twelve balls in the hopper 4.

The plurality of balls comprising the "deck" are dumped into the hopper 4 from the chute 7 and gravitate to the trough 17 for approximate uniform annular distribution therein, and are 65 then circumferentially agitated so as to drop through discharge ports 18 for filling the respective tubes 5. For this purpose a vertical shaft 19 may project through the top of housing 1 and may be provided with a handle 20 for rotating 70 or oscillating the shaft, and radial fingers 21 project from the shaft into the trough 17 as shown at Fig. 3, for distributing the balls to the respective discharge posts 18 when the shaft is turned.

75 The playing units, which each comprise a sta-

tion 3 and its discharge tube 5, are of similar construction so that a description of one will suffice for all.

The station 3 comprises a trough 25 extending parallel to that wall of housing 1 at which the station is positioned, with the trough at the inner surface of the wall and adapted to receive balls from the tube 5 and to support the balls one behind another, and to hold a number of balls corresponding to the number of cards constituting a complete hand, which in the present instance is five balls. The trough is visible to the player at that station, and for this purpose an opening 26 is formed in the wall of housing 1 in front of trough 25, and a frame 27 is mounted 15 in the opening so as to support the trough and provide a glass-covered sight opening 28 through which the player at that station may see the trough, while shielding it from the vision of the other players standing in front of the other stations of the apparatus. The trough is inclined as shown at Fig. 4, so that the balls received from tube 5 tend to roll along the trough and drop from its lower end, but a pivoted gate is provided for retaining the balls in the trough. 25

The gate includes a back bar 29 and an end bar 30, and is pivoted to frame 27 as shown at 31, so that when swung to the position shown at Fig. 6 the balls 15 are free to roll along the trough 25 and drop from the same, and when swung downwardly to the position shown at Fig. 7 the bar 30 holds the balls against dropping from the end of the trough but the bar 29 is in a position offering no obstruction to the balls being pushed off the back of the trough, and when swung further downwardly to the position shown at Fig. 8 the bar 30 holds the balls against dropping from the end of the trough and the bar 29 prevents the balls being pushed off the back of the trough. 40

When the gate is in the position shown at Fig. 7 with the initial hand of five balls supported in trough 25 and displayed at sight opening 28, the player at that station may remove any of the balls which he wishes to discard. For this 45 purpose a plurality of plungers 32 (Fig. 6) normally spring retracted as shown at 33, are mounted in frame 27 for alignment with the respective balls which are supported in trough 25, and are adapted for selective projection by the player 50 so that any desired ones of the displayed balls may be pushed off the back of the trough. The remaining balls, if any, then roll to the lower end of the inclined trough where they are held by bar 30, and thus provide space for reception from 55 tube 5 of a number of balls corresponding to the number which have been discarded.

The discharge tube 5 slopes downwardly and its outlet end is curved as shown at 35 for alignment with the trough 25, so that the balls 15 60 will freely gravitate through the tube and discharge into the trough and roll along the same; and the number of balls discharged into trough 5 is manually controlled, in the present instance by the corresponding set of knobs 13. For this 65 purpose a retractible abutment pin 36 may control discharge of balls from the tube into the trough, and a plurality of abutment pins 37 may be arranged for selective projection for determining the number of balls which are discharged 70 each time the pin 36 is retracted. The pin 36 is guided as shown at 38 and is normally projected by a spring 39 so as to extend across the bore of tube 5 adjacent its outlet end for obstructing passage of balls 15 as shown at Fig. 14, 75

but may be retracted by a finger 40 so as to clear the bore of tube 5 and thus permit free passage of the balls. The pins 37 are adapted for projection across the bore of tube 5 to interrupt passage of balls 15 as shown by broken lines at Fig. 13, and are spaced from one another lengthwise of tube 5 and in back of pin 36, such units of space as just provide for reception of a single ball 15 between adjacent pins 37 and between pin 36 and the proximate pin 37, and in the present instance the pins 37 are five in number so as to provide five of said unit spaces. The pins 37 are normally retracted so as to clear the bore of tube 5, as shown by full lines at Fig. 13, and a selected one of said pins is adapted for operative projection at the same time that pin 36 is retracted, so that a number of balls are released for discharge into trough 25, corresponding to the number of units of space between the pin 36 and that one of the pins 37 which has been projected. For example if the pin 37 next to pin 36 is projected when pin 36 is retracted, only the single ball which is in front of this pin 37 is discharged into trough 25, while if the pin 37 which is remote from pin 36 is projected when pin 36 is retracted, the five balls in front of this pin 37 are discharged into trough 25. In similar manner selective projection of the intermediate pins 37 causes discharge of either two, three or four balls.

The means for projecting a selected pin 37 and at the same time retracting the pin 36, may comprise a bar 41 extending lengthwise of tube 5 below the same, with finger 40 projecting upwardly from the bar and engaging an abutment 42 on the stem 36a of the pin 36. The pins 37 have U-shaped stems 37a beneath the tube 5 and terminating in slides 43 which extend through bar 41 and upwardly through guides 44 at the side of tube 5, and springs 45 on the pins 37 normally retract the respective pins, and abutments 46 on the slides 43 are adapted to engage the bar 41. The bar 41 is normally retracted as shown at Fig. 6, by means of a spring 47 mounted on a guide pin 48 which projects upwardly from bar 41 and which is slidably received in a bracket 49 on the tube 5; and by pulling on any selected one of the slides 43, its pin 37 is operatively projected across the bore of tube 5 and its abutment 46 engages and elevates bar 41 so as to simultaneously project the finger 40 for retracting the pin 36, with the bar 41 sliding freely along the other slides 43 so that their pins 37 remain in normal inoperative retracted position. This movement of the parts is shown at Fig. 7, the slide 43 for the pin 37 which is remote from pin 36 having been actuated for discharging five balls from the tube 5 into the trough 25, to provide the initial poker hand.

Tension on the slide 43 which has been actuated is then released, so that the spring 47 returns the bar 41 to normal position, thereby retracting the pin 37 which has been operatively projected and at the same time permitting spring 39 to again operatively project the pin 36. The player then discards from his hand by selectively pushing the plungers 32, and after the discard tension is again exerted on one of the slides 43 for again elevating the bar 41 to project the corresponding pin 37 and at the same time retract the pin 36 for discharging the proper number of balls to refill the hand. This movement of the parts is shown at Fig. 8, the slide 43 for the middle pin 37 having been actuated for discharging three balls to refill a hand from which this number of balls has been selectively discarded.

Tension may be exerted on a selected slide 43 by means of cables 51 extending from the respective slides to the respective knobs 13 of that set of knobs which is provided for the corresponding discharge tube 5; and when playing poker the "dealer" in turn pulls that knob of the successive stations which causes five balls to be supplied to the respective stations, and after the players each discard and as they in turn call for cards, the "dealer" refills the hands by pulling that knob 10 for the respective stations which supplies the number of balls requested by the respective players.

At each station the bar 41, after having been elevated and then returned to normal position 15 for initially dealing a hand, and subsequently elevated once and then returned to normal position for refilling the hand after the discard, is locked against further elevation until play is completed by dumping all of the balls onto the 20 sloping base 9 of the housing 1, preparatory to playing a new hand.

As an instance of this arrangement a shaft 52 may be journaled across each of the discharge tubes 5 and has a control lever 53 at one end. 25 A ratchet 54 is fixed on the shaft and is adapted for engagement by a pawl 55 which is pivoted on bar 41 as shown at 56 and which is yieldably projected by a spring 57. When the bar 41 is in normal position as shown at Fig. 6, the pawl 30 55 engages an abutment 58 which holds the pawl out of engagement with the ratchet, but when the bar 41 is elevated so that the pawl is clear of the abutment, the pawl is swung by its spring 57 to a position engaging the ratchet as shown at 35 Figs. 7 and 8. The ratchet has three teeth, and with the parts in the position shown at Fig. 6 elevation of bar 41 for initially dealing a hand, engages the pawl with the first tooth 59 for rocking the shaft 52 to the position shown at Fig. 7, 40 and when the bar 41 is subsequently returned to normal position the spring 57 allows the pawl to yield so as to ride freely over the ratchet without turning the shaft. The parts are thus positioned so that when bar 41 is again elevated for refilling 45 the hand, the pawl engages the second tooth 59a for turning the shaft 52 to the position shown at Fig. 8, where an abutment 60 of the ratchet engages a stop 61. Return of bar 41 to normal position then causes the pawl to again ride freely 50 over the ratchet without turning the shaft so as to align the pawl with the third tooth 59b, but since the ratchet is then locked against further turning by the engagement at 60—61, the bar 41 is locked against being again elevated due to 55 the engagement of the pawl 55 with the tooth 59b.

Means are preferably provided for holding the ratchet against accidental reverse rotation when in each of its intermittently rotated positions, 60 and for this purpose a spring projected dog 63 may cooperate with a series of notches 64 at the periphery of the ratchet 54, with one of said notches adapted for yieldable engagement by the dog when the ratchet is turned to each of the 65 positions shown at Figs. 6, 7, and 8.

The gate 29—30 is swung to the respective positions shown at Figs. 6, 7, and 8, by the intermittent rotation of shaft 52. For this purpose a lever 65 is fixed on shaft 52 and is connected 70 by a link 66 to the back bar 29 of the pivoted gate, so that at the start of play the gate will have been swung to inoperative position by the lever 65 (Fig. 6), and when the initial hand is dealt the gate is swung to position holding the balls against 75

rolling out of the trough at its lower end but permitting them to be pushed off the back of the trough by the plungers 32 (Fig. 7), and when the discard has been made and while the hand is being refilled, the gate is swung to position locking the balls against rolling out the end of the trough on being pushed off the back of the same (Fig. 8).

At the end of play all of the remaining balls are discharged from the tubes 5 into the troughs 25 and are then dumped from the lower ends of the troughs onto the sloping base 9 for return to the elevator 6. This is accomplished by actuating the control lever 53 at each station, so as to swing the shaft 52 from the position shown at Fig. 8 back to the position shown at Fig. 6 where the tooth 58b is adapted to engage a stop 66. The bar 41 is not elevated during this operation, and the abutment 58 thereby holds the pawl 55 out of engagement with the ratchet 54 to permit such reverse rotation of the shaft 52.

As a result of this reverse rotation of the shaft 52, the lever 65 returns the gate 29-30 to inoperative position as shown at Fig. 6, so that the balls 15 are free to roll along the trough 25 and drop off at its lower end, and the movement of lever 53 to produce this reverse rotation of the shaft is adapted to retract the pin 36 while leaving all of the pins 37 in their normal inoperative position, so that all of the remaining balls in the tube 5 are discharged therefrom.

As an instance of this arrangement a lever 67 is pivoted above the tube 5 and is connected by a link 68 to the lever 53; and a second link 69 is connected to the lever 67 and engages a head 73 on the stem 36a of the pin 36. The link 68 is freely slideable through a swivel 71 on the lever and has an end abutment 72 adapted to engage the swivel. Upward swing of the lever 67 is thus adapted to elevate the link 68 as shown at Fig. 4, but the lever 67 may then be swung downwardly without disturbing the link 68, since the swivel 71 will slide freely along the link to provide a lost motion connection between the link 68 and the lever 67 as shown at Fig. 5. The link 68 terminates in an eye 73 which is freely slideable on the stem 36a and which is adapted to engage the head 70. Upward swing of the lever 67 is thus adapted to retract the pin 36 against the tension of its spring 39 as shown at Fig. 4, without disturbing the finger 40, and when the lever 67 is swung downwardly the pin 36 is operatively projected by its spring 39, and may then be retracted by its finger 40 with the stem 36a sliding freely through the eye 73 so as to provide a lost motion connection between the stem 36a and the link 69 as shown at Fig. 7.

At the end of play the lever 67 is swung to its upper position as shown at Fig. 4, for retracting the pin 36 and reversely rotating the ratchet 54 and opening the gate 29-30 for dumping the balls as previously described, and the levers 67 for the plurality of stations 3 are connected for dependent operation so as to dump the balls at all of the stations. For this purpose a lever 75 is adapted to swing each of the levers 67; and by means of bell cranks 76 and linkage 77, the levers 75 are connected for dependent operation as shown at Fig. 1. A link 78 is connected to one of the levers 75, so that by retracting this link at the end of play all of the levers 67 are swung upwardly as shown at Fig. 4, thereby discharging all of the balls from the tubes 5 into the troughs 25 and from thence dumping all of the balls onto base 9. By projecting the link

78 when a new hand is to be played, all of the levers 67 are swung downwardly as shown at Fig. 5, with the swivels 71 sliding idly along the links 68 and the eyes 73 sliding along stems 36a to permit operative projection of the pins 36 by their springs 39. During subsequent play of the hand each shaft 52 is intermittently rotated and the pins 36 and 37 are retracted and projected by pulling the knobs 13 as previously described, with the lost motion connection 71-72 permitting such rotation of the shaft and the lost motion connection 70-73 permitting such movement of the pins.

The coin control 12 is preferably arranged so as to necessitate the insertion of a coin before a hand may be played. For this purpose the coin control may include a usual slide 79 which may be freely retracted from housing 1 but which is then locked against projection into the housing until a proper coin is inserted in the slide; and the link 72 is connected to the slide 79 as shown at Figs. 4 and 5, so that by retracting the slide at the end of play the movement of link 78 causes all the balls to be dumped as previously described, thereby rendering the apparatus inoperative until a coin is inserted, whereupon the slide 79 may be projected into the housing 1 for projecting the link 73 so as to again position the parts ready for play by operating the knobs 13.

The elevator 6 is adapted to receive the balls 15 when they are dumped onto the base 9 at the end of play of a hand, and is adapted to then elevate the balls and dump them into chute 7 and thence into hopper 4 preparatory to playing a new hand. For this purpose the elevator may be mounted on a guide rod 81 for vertical sliding movement controlled by the handle 10; and the elevator comprises a container open at its top and having a hinged gate 82 at its front side, with the base of the container sloping downwardly toward the gate as shown at 83. The gate 82 is held in closed position until the elevator reaches its upper limit of movement and is then automatically opened so as to bridge the space between the base 83 and the chute 7 to allow the balls to roll onto the chute. As an instance of this arrangement the gate 82 is hinged at its lower edge as shown at 84, and a vertical guide rod 85 is positioned in front of the elevator and is curved at its upper end as shown at 86, so that until the elevator reaches its upper limit of movement the gate is engaged by rod 85 to hold the gate in closed position as shown by full lines at Fig. 9, but when the elevator reaches its upper limit of movement the curved end 86 of the guide rod permits the gate to swing open and rest upon chute 7 as shown by broken lines at Fig. 9. When the elevator is subsequently lowered, its gate is reclosed by its engagement with the guide rod 85.

When the elevator is in its lowered position it is received in well 8 below the level of sloping base 9, with the balls 15 adapted to drop into the elevator from the sloping base via the open top of the elevator, but when the elevator has been moved upwardly along its guide rod 81 a gate 88 preferably shuts off the well 8 from the sloping base 9 so as to arrest the balls except when the elevator is in position to receive the same. The gate 88 is slideable on a guide rod 89 for vertical movement in the well 8 between the elevator and the wall of the well, and has a spring 90 tending to elevate the gate to its limit of movement as determined by a

stop 91, and has depending fingers 92 adapted to hook under the elevator. When the elevator is lowered into the well it engages fingers 92 to depress the gate 88 against the tension of its spring 90 as shown in full lines at Fig. 9, so that the gate is below the level of base 9 and the balls 15 are thus free to drop into the elevator, but when the elevator is lifted the gate 88 is elevated by its spring 90 so as to project above the base 9 as shown by broken lines at Fig. 9, thereby preventing the balls 15 from dropping into the open elevator well.

The elevator 6 is preferably locked against elevation to its dumping position until a coin has been inserted at the coin control 12, and when a coin has been inserted and the elevator released, its elevation to dumping position is adapted to project the slide 79 into the housing 1, so that the pins 36 are operatively projected 20 as previously described for shutting off the discharge tubes 5 before the balls 15 are dumped into the chute 7 and thence into the hopper 4.

As an instance of this arrangement an arm 95 is pivotally mounted for engagement by the elevator 6 as it approaches its dumping position, for swinging the arm from the position shown in full lines to that shown by broken lines at Fig. 9; and the arm 95 is fixed on a transverse shaft 96 which is journaled on the front wall of casing 1 as shown at Fig. 1, and which has a lever 97 fixed thereto and connected by a link 98 to one of the levers 75 as shown at Fig. 4. With the slide 79 locked in retracted position until a proper coin is inserted the link 98 locks the lever 97 in the position shown at Fig. 4 and thus locks the arm 95 in the position shown in full lines at Fig. 9, for arresting elevation of the elevator 6 before it reaches its dumping position, and thus prevents the balls 15 being supplied to the discharge tubes 5. After a coin has been inserted so as to release the slide 79 for free sliding projection into housing 1, the elevator may be lifted to its dumping position, since its engagement with arm 95 will swing the arm to the position shown by broken lines at Fig. 9, the arm being free to swing due to the fact that the link 98 is now free for movement as a result of the slide 79 having been released. The movement of link 98 which results from the swinging of arm 95 and which is shown at Fig. 5, swings the levers 75 for depressing the levers 67 as previously described, thereby permitting springs 39 to operatively project the pins 36 so that the discharge tubes 5 are shut off. The arm 95 is so positioned that the link 98 will have completed its movement by the time the elevator 6 reaches its upper limit of movement and dumps, and therefore the pins 36 will have shut off the discharge tubes 5, ready for controlled discharge of balls by actuating the knobs 13, by the time that the balls have dumped into chute 7 and gravitated thence into hopper 4 and through ports 18 into the discharge tubes.

To summarize operation of the device, at the start of play the parts are in the position shown at Figs. 1 and 4 with all of the balls 15 collected in the elevator 6 which is lowered into well 8, and by usual coin-control mechanism associated with slide 79 the latter is automatically locked against projection into casing 1 until a proper coin is inserted. The "dealer" inserts a coin for releasing the slide 79, and then raises the elevator 6 so as to dump the balls 15 into the hopper 4, thereby rocking the shaft 97 for projecting the slide 79 into casing 1 so that the parts assume

the position shown at Figs. 5 and 6 with the pins 36 operatively projected and preventing discharge of balls from the tubes 5 into the troughs 25. By oscillating the handle 20 the "dealer" thoroughly mixes the balls in hopper 4 and moves them around the trough 17 so as to distribute them to the various ports 18 for filling the respective tubes 5; and the "dealer" then in turn pulls that knob 13 of each successive station 3 which controls discharge of five balls to the corresponding trough 25, thereby dealing a poker hand to each station. This operation swings the gates 29-30 to the position shown at Fig. 7, so that the balls constituting each poker hand are held against end discharge from the trough 25 but may be selectively pushed off the back of the trough by manually projecting the corresponding plungers 32. The hand at each station is visible to the player at that station through the sight opening 28 but is concealed by casing 20 1 from the players at the other stations, and when each player has viewed his hand he pushes desired ones of the plungers 32 at his station for selectively discarding from his hand. The players then in turn announce the number of their 25 discard and the "dealer" by pulling the proper knob 13 of the successive stations refills the hands so that each hand again comprises five balls. This operation swings the gates 29-30 to the position shown at Fig. 8 so that the balls 30 then constituting the hand at each station are held against end discharge from the trough 25 and are also held against being pushed off the back of the trough. To complete the play the "dealer" pulls out the slide 79, thereby returning the parts to the position shown at Figs. 1 and 4 and thus retracting the pins 37 and swinging the gates 29-30 to open position so that all of the balls are dumped onto the base 9 from whence they gravitate to the elevator 6 which 40 has again been lowered into the well 8; and when slide 79 is thus retracted it is automatically locked, thereby locking the machine against further play until a new coin is inserted.

We claim:

1. In a game apparatus, a playing station, a plurality of playing elements each having an identifying symbol, gravity means for supplying a predetermined number and chance determined combination of playing elements to the playing 50 station, means for selectively removing playing elements from the station, and gravity means for supplying the station with a number of playing elements corresponding to the number which has been removed therefrom.

2. In a game apparatus, a playing station, a plurality of playing elements each having an identifying symbol, a container for the playing elements, means for supplying a predetermined number and chance determined combination of 60 playing elements from the container to the playing station, a second container, means for selectively removing playing elements from the station and discharging the same into the second container, and means for supplying the playing 65 station from the first container with a number of playing elements corresponding to the number which has been removed from the station.

3. In a game apparatus, a playing station, a plurality of playing elements each having an 70 identifying symbol, a container for the playing elements, means for supplying a predetermined number and chance determined combination of playing elements from the container to the playing station, a second container, means for selec- 75

- tively removing playing elements from the station and discharging the same into the second container, means for supplying the playing station from the first container with a number of playing elements corresponding to the number which has been removed from the station, means for discharging playing elements from the first container and from the playing station into the second container, and means for returning the playing elements from the second container to the first container.
4. In a game apparatus, a plurality of playing stations, a plurality of playing elements each having an identifying symbol, means for supplying a predetermined number and chance determined combination of playing elements to the respective stations, means for selectively removing playing elements from the respective stations, means for supplying the respective stations with a number of playing elements corresponding to the number which has been removed from the respective stations, and means accessible to a player at one of the stations for controlling the supply means for the plurality of stations.
5. In a game apparatus, a playing station, a discharge tube leading to the station, a plurality of independent and separately movable playing elements each having an identifying symbol, means for supplying playing elements to the tube, and means for controlling discharge of playing elements from the tube to the playing station.
6. In a game apparatus, a playing station, a discharge tube leading to the station, a plurality of independent and separately movable playing elements each having an identifying symbol, means for supplying playing elements to the tube, and control means for discharging a selected number of playing elements from the tube to the playing station.
7. In a game apparatus, a playing station, a plurality of playing elements each having an identifying symbol, means for supplying playing elements to the station, means for controlling the supply means, means for selectively removing playing elements from the station, and means for locking the controlling means after being twice actuated.
8. In a game apparatus, a playing station, a plurality of playing elements each having an identifying symbol, means for supplying playing elements to the station, means for controlling the supply means, means for selectively removing playing elements from the station, means for locking the controlling means after being twice actuated, means for discharging all of the playing elements and means whereby actuation of the last mentioned means releases the locking means.
9. In a game apparatus, a playing station, a plurality of playing elements each having an identifying symbol, means for supplying playing elements to the station, means for controlling the supply means, means for selectively removing playing elements from the station, a gate for the playing station, and an operating connection whereby initial actuation of the controlling means renders the gate inoperative so as to permit playing elements being removed from the station and subsequent actuation of the controlling means operates the gate to prevent playing elements being removed from the station.
10. In a game apparatus a plurality of playing stations, a discharge tube leading to each station, a plurality of independent and separately movable playing elements, means for supplying playing elements to the discharge tubes, means for controlling discharge of playing elements from the respective stations to the corresponding playing stations, means for selectively removing playing elements from the respective stations, means for locking the controlling means for each tube after being twice actuated, means for discharging all of the playing elements from the plurality of discharge tubes and from the corresponding playing stations, and means whereby actuation of the last mentioned means releases the locking means for the plurality of discharge tubes.
11. In a game apparatus a plurality of playing stations, a discharge tube leading to each station, a plurality of independent and separately movable playing elements, means for supplying playing elements to the discharge tubes, means for controlling discharge of playing elements from the respective tubes to the corresponding playing stations, means for selectively removing playing elements from the respective stations, means for discharging all of the playing elements from the plurality of discharge tubes and from the corresponding playing stations, means for locking said last mentioned means in discharging position, and coin controlled means for releasing said locking means.
12. In a game apparatus, a playing station, a hopper, a discharge tube leading from the hopper to the station, a plurality of independent and separately movable playing elements each having an identifying symbol, means for elevating the playing elements into the hopper for gravity supply to the discharge tube, means for controlling discharge of playing elements from the tube to the playing station, and means for returning playing elements from the station to the elevating means.
13. In a game apparatus, a playing station, a hopper, a discharge tube leading from the hopper to the station, a plurality of independent and separately movable playing elements each having an identifying symbol, means for elevating the playing elements into the hopper, means for mixing the playing elements in the hopper and supplying the same to the discharge tube, and means for controlling discharge of playing elements from the tube to the playing station.
14. In a game apparatus, a playing station, a plurality of playing elements each having an identifying symbol, a container for the playing elements adapted for chance determined irregular distribution of the playing elements therein, means for supplying a predetermined number and chance determined combination of playing elements from the container to the playing station, a second container, means for discharging playing elements from the station into the second container, and means for returning playing elements from the second container to the first container.
15. In a game apparatus, a playing station, a plurality of playing elements each having an identifying symbol, a container for the playing elements adapted for chance determined irregular distribution of the playing elements therein, means for supplying a predetermined number and chance determined combination of playing elements from the container to the playing station, a second container, means for selectively removing playing elements from the station and discharging the same into the second container, and means for supplying the playing station from the first container with a number of playing ele-

ments corresponding to the number which has been removed from the station.

16. In a game apparatus, a playing station, a plurality of playing elements each having an identifying symbol, a container for the playing elements adapted for chance determined irregular distribution of the playing elements therein, means for supplying a predetermined number and chance determined combination of playing elements from the container to the playing station, a second container, means for selectively removing playing elements from the station and discharging the same into the second container, means for supplying the playing station from the first container with a number of playing elements corresponding to the number which has been removed from the station, means for discharging playing elements from the first container and from the playing station into the second container, and means for returning playing elements from the second container to the first container.

17. In a game apparatus, a playing station, a plurality of playing elements each having an identifying symbol, a container for the playing elements adapted for chance determined irregular distribution of the playing elements therein, means for supplying a predetermined number and chance determined combination of playing elements from the container to the playing station, a second container, means for selectively removing playing elements from the station and discharging the same into the second container, means for supplying the playing station from the first container with a number of playing elements corresponding to the number which has been removed from the station, means for discharging playing elements from the playing station into the second container, and means for returning playing elements from the second container to the first container.

18. In a game apparatus, a playing station, a plurality of playing elements each having an identifying symbol, means for supplying playing elements to the station, means for discharging playing elements from the station, means for locking said last mentioned means in discharging position, and coin controlled means for releasing said locking means.

19. In a game apparatus, a playing station, a plurality of playing elements each having an identifying symbol, a container for the playing elements adapted for chance determined irregular distribution of the playing elements therein, means for elevating the playing elements into the container for gravity supply therefrom to the playing station, and means for returning playing elements from the playing station to the elevating means.

20. In a game apparatus, a playing station, a plurality of playing elements each having an identifying symbol, a container for the playing elements adapted for chance determined irregular distribution of the playing elements therein, and means for elevating the playing elements into the container for gravity supply therefrom to the playing station.

21. In a game apparatus, a playing station, a plurality of playing elements each having an identifying symbol, gravity means for supplying playing elements to the station, and means for selectively removing playing elements from the station.

22. In a game apparatus, a playing station,

a plurality of playing elements each having an identifying symbol, gravity means for supplying playing elements to the station, and means for selectively displacing playing elements with relation to the station so as to gravitate therefrom. 5

23. In a game apparatus, a playing station, a plurality of playing elements each having an identifying symbol, gravity means for supplying playing elements to the station, and control means associated with said gravity means and including means whereby actuation of the control permits only a predetermined number of playing elements being supplied to the station

24. In a game apparatus, a plurality of playing stations, a plurality of playing elements each having an identifying symbol, a plurality of means for supplying playing elements to the respective stations, and means associated with each of said plurality of supply means for controlling the number of playing elements supplied thereby, the control means for the respective supply means being independently operable but all being accessible for actuation by a player at one of the stations.

25. In a game apparatus, a playing station, a plurality of playing elements each having an identifying symbol, and a container for the playing elements having an outlet arranged for successive unit passage of playing elements through said outlet to the playing station, the container being arranged to receive and contain the entire plurality of playing elements at one time, with the entire plurality of elements spread out around the outlet in chance determined relationship whereby the last or any preceding one of the playing elements to enter the container may first 35 aline with the outlet for passage therethrough.

26. In a game apparatus, a playing station, a plurality of playing elements each having an identifying symbol, a container for the playing elements having an outlet arranged for successive 40 unit passage of playing elements through said outlet to the playing station, and means for dumping the entire plurality of playing elements into the container at one time and in chance determined relationship, the container being adapted 45 to contain the entire plurality of playing elements at one time, with the entire plurality of playing elements spread out around the outlet in chance determined relationship whereby any one of said playing elements may first 50 aline with the outlet for passage therethrough.

27. In a game apparatus, a playing station, a plurality of playing elements each having an identifying symbol, a container for the playing elements, gravity means for supplying playing elements from the container to the station, a second container, gravity means for discharging playing elements from the station into the second container, and means for returning playing elements from the second container to the first container. 60

28. In a game apparatus, a plurality of playing stations, a plurality of playing elements, means for supplying playing elements to the respective stations, and means whereby the playing elements at each station are visible to a player at that station but are concealed from the players at all other stations, said last mentioned means including means preventing access to the playing elements such as would permit their removal from the game apparatus. 65
